UNITED STATES PATENT OFFICE.

JAY J. SINDLER, OF FRAMINGHAM, MASSACHUSETTS, ASSIGNOR OF ONE-HALF TO
CALVERT B. ARCHER, OF SHERBORN, MASSACHUSETTS.

GAME.

Application filed November 15, 1923. Serial No. 674,828.

To all whom it may concern:

Be it known that I, JAY J. SINDLER, a citizen of the United States of America, and resident of Framingham, in the county 5 of Middlesex and State of Massachusetts, have invented new and useful Improvements in Games, of which the following is a specification.

The present invention includes a game 10 or amusement device, and means whereby it may be adapted for various modes of playing.

The invention comprises a container having pockets in the bottom, indicators which 15 may be distributed among the pockets by chance (as by shaking the container) and a transparent top, through which the indicators may be observed and upon which symbols may be placed, to evaluate their positions. Means are also provided whereby 20 the device may be adapted to numerous games and to different conditions of playing them.

The objects and other features of the invention will sufficiently appear from the following disclosure and claims.

A device in which the elements of my invention are typically exemplified will be described and illustrated by the accompanying drawings.

Fig. 1 is a plan view of the device with symbols corresponding to a set of playing cards;

Fig. 2 is a perspective view of the same 35 with cover closed;

Fig. 3 is a vertical section of the same on line 3—3, Fig. 1;

Fig. 4 is a vertical longitudinal section of the same on line 4—4, Fig. 1;

Fig. 5 is a plan view of a transparent cover plate with letters thereon;

Fig. 6 is a plan view of a transparent cover plate with figures thereon; and

Fig. 7 is a plan view of a modification of 45 said game.

With reference to the drawings, the container of the game is simply a covered box 1 made of pressed metal, with a bottom 2, and a cover 7 hinged to the rear of 50 the box 1. Fitted into said box are side walls 3, front wall 4 and rear wall 6 made of wood and joined at the corners.

On the inner surface of the bottom 2

there are provided a plurality (in the present instance 52) of pockets 8. The pockets 55 may be regularly or irregularly disposed over the bottom, and may be varied in size and shape if desired, but are shown as hemispherical depressions of equal size and symmetrically spaced in eight rows 9 of alternately 6 and 7 pockets each. Indicators 11 which are preferably spherical in shape, are loosely contained in the box and adapted to fit the pockets 8. These indicators are preferably of less diameter than the pockets 60 65 and may be differently colored if desired.

Adjacent the upper, inner edges of side walls 3 and rear walls 6 are provided grooves 12 parallel to the upper edge and connecting at the corners of the box. The upper portion of the front wall 4 is level with the lower edge 13 of the groove 12 permitting the insertion of a transparent slide 14, as of glass, celluloid or the like, therein. This slide is of such thickness as to loosely fit 75 the height of the grooves 12 and of such length and width as to slide smoothly therein. Spring catch 16 in the front wall 4 is adapted to snap up behind the slide and is held firmly in position. 80

The cover 7 is preferably opaque and adapted to fit over the top of the box and may be fastened in place by the latch 17.

The transparent cover plate or slide 14, (Fig. 1) is provided with symbols (preferably in broken arrangement) 1, 2, 3, 4, 5, 6, 7, 8, 9, 10, J, Q and K respectively, for each suit contained in the ordinary set of playing cards (diamonds, hearts, spades and clubs). Each symbol, when the plate is in 85 90 position shown in Fig. 1, stands immediately above a pocket 8 corresponding thereto. A transparent card 18 of the same width as the cover plate and adapted to slip over the cover plate in the grooves 12 may also be provided. This may be colored if desired and has an aperture 19 of sufficient size in the central portion so that it will outline any predetermined group of symbols in the transparent slide (such as the "hearts" suit 100 in Fig. 1).

In use, as for example to play poker, each player is provided with a device such as the one illustrated. Five indicators 11 are placed in each container and with the transparent cover plate in position as shown, the 105

outer cover is closed down. The boxes are then shaken. Each player observes his result. If he wishes to "discard" he may shake a second time. After observing his result, each player closes his box, places it flat on a table and bids upon his "hand" in sequence, according to the usual rules. Upon "call" all boxes are opened and compared, and the same values applied to the hands, (as determined by the positions of the indicators) as when the game is played with cards.

In a modified form of the game (Fig. 7) opposing slots 5 are provided in side walls 3 adapted to receive a vertical slide or partition 10 therein of sufficient length and height to extend across the box and prevent the indicators from passing. Thus, in the position shown in Fig. 7 the indicators 11 can not pass into the first two rows of pockets, and a game may be played in which 39 pockets only are used. By placing this partition in other slots the number of pockets may be varied at will. For some games it will be removed entirely, as in the instance above described.

Other games may be played with the device thus provided, the number of players, number of indicators, number of pockets, etc., being varied accordingly, as will be readily suggested by the conditions of play. The slide 14 may be replaced with other slides 21 or 22 by depressing the catch 16 withdrawing it from the grooves 12 and introducing the new slide into position for playing a still wider variety of games, or for use as a solitaire amusement.

These interchangeable slides may be provided with any desired symbols or combination of symbols. For example the slide 21 shown in Fig. 5 bears a group of letters, spaced thereon to correspond to the pockets 8. In this case, the indicators will spell words and the like by their arrangements in the pockets. As a further example, the slide 22 shown in Fig. 6 is provided with numerals and the device may be used for providing problems of arithmetic such as the addition, multiplication, etc., of the numbers indicated.

Numerous other games may be played with the device by simple changes which will readily occur to one who has used it as described. It is small and compact, and the elements are not subject to loss, which is commonly experienced with cards and the like even while playing. It is adaptable for use by any number of players, collectively and individually, as desired, and according to the general rules, or with slight modifications. Such variations and modifications, however, constitute a part of this invention and are comprehended by the following claims.

I claim:

1. A game or amusement device comprising a plurality of indicator receiving pockets, an indicator loosely held therein, an open topped container for the same, a transparent sheet placed above said pockets and closing said container, and symbols upon said sheet so disposed as to correspond with said pockets. 65

2. A game or amusement device, comprising a container, a plurality of indicator-receiving pockets in the interior of the bottom thereof, an indicator loosely contained therein, and a transparent cover removably secured to the upper portion of said container and bearing spaced symbols thereon corresponding to said pockets. 75

3. A game or amusement device comprising a box, indicator-receiving pockets on the interior of the bottom thereof, an indicator therein, a transparent cover fixed upon the top of the box, and symbols upon said transparent cover corresponding to said pockets and representing a set of playing cards. 80

4. A game or amusement device, comprising a box, indicator-receiving pockets on the interior of the bottom thereof, a transparent slide adjustably mounted in the top of the box, symbols upon said slide corresponding to said pockets and representing a set of playing cards, an opaque cover adapted to fit over said transparent slide, and an indicator member loosely contained in said box. 90

5. A game or amusement device, comprising a container, a plurality of indicator-receiving pockets therein, a transparent plate above said pockets, symbols upon said transparent plate corresponding to said pockets, an indicator loosely contained in said pockets, and a guide card slidably mounted above said transparent plate and adapted to outline a predetermined group of said symbols. 100

6. A game or amusement device, comprising a container, a plurality of indicator-receiving pockets therein, a transparent plate above said pockets, an indicator loosely contained therebetween and an adjustable partition mounted within said container adapted to prevent said indicator from falling into a predetermined group of said pockets. 115

7. In a game or amusement device, a container for movable indicators, indicator-receiving pockets, and a transparent cover having symbols in predetermined arrangement thereon representing a set of playing cards and corresponding to said indicator-receiving pockets. 120

8. A device of the class described comprising a shallow box having a plurality of substantially hemispherical pockets in its bottom, a spherical indicator in the box of a diameter less than that of the pockets, a transparent cover plate spaced from the

bottom of the box to permit the indicator to move freely from one pocket to another, and a distinguishing symbol upon the cover plate directly over each pocket.

5 9. A device of the class described comprising a shallow box having a plurality of pockets in its bottom, an indicator movable from one pocket to another, and a plurality

of transparent interchangeable cover plates for the box provided with symbols for designating the several pockets, the symbols of the respective plates being different. ¹⁰

Signed by me at Boston, Massachusetts, this 13th day of November, 1923.

JAY J. SINDLER.
